SYSTEM OF SIGNALS

Application filed August 20, 1926. Serial No. 130,531.

This invention refers to a system of signs which avoid the collisions of trains, specially electric trains, although the system may be applied to trains which run by steam or crude oil, and has for its main object the provision of an arrangement such as will operate a luminous or acoustic signal, which may be noticed by the driver of the train, when it occurs that another train is coming in an opposite direction on the same track or even in the same direction.

My invention provides therefore, a very simple and cheap arrangement, by which open circuits are practically formed in a moving train upon a section of railroad equipped with trolley wires, which circuits remain closed, when it occurs that another train is running in the same or opposite direction on the same road section or is standing still on same, and on which train are also formed open circuits corresponding with the former to complete the closing of same, producing a signal on each train, which must inevitably be seen or heard by the conductor of the train. Another object of the invention is to provide an arrangement which permits the using of the system for causing same to operate signals on crossings in the road.

More advantages and other considerations pertaining to this invention will be found in the course of this specification, specially by those experts in the art to which this invention pertains, and with the aid of the figures in the attached drawings in which the same characters of reference designate the same parts.

In the drawings:

Fig. 1 is a diagrammatical plan view which shows a section of railroad and trains on same, wherein is installed the signal system which forms the object of this invention.

Fig. 2 is a side elevation of said section of road thus equipped.

Fig. 3 is a diagrammatical front elevation view on an enlarged scale of a car and a sec-

tion of road equipped with the system which is the object of this invention.

Fig. 4 is a diagrammatical side elevation in detail of a car equipped with the corresponding part of the system.

Fig. 5 is an upper plan view of Fig. 4.

Let us consider a section of road, on which run north bound and south bound trains.

Along the track in any predetermined sections, posts 1 are erected bearing brackets 2 on which are fastened brackets 3 for holding insulators 3' and holders 3" for the trolley wires 4. The trolley wires 4 are extended throughout the length of each section. Each locomotive or railway car is provided with a signal apparatus which forms the object of this invention and will hereinafter be described and illustrated in the attached drawings.

Mounted on the roof of the car upon a base 6 is an oscillating trolley holder comprising a vertical shaft 6 having a longitudinal slot 6' in which a horizontal member 7 is held. The horizontal member 7 is bent upwardly at its ends to form a standard 7' to bear fork holders 8 between which is loosely mounted the trolley 9.

The horizontal member 7 is braced by T's 10 which are hinged to member 7 at their upper ends and at their lower extremities 75 hinged to a slideable collar 11 mounted on shaft 6. The slideable collar 11 is supported by a spiral spring 12 coiled around the shaft 6 and bearing on its lower end on a collar 13 fastened to said shaft. The source of current 80 supply is from generator C mounted in car B. Generator C has two binding posts 14 and 19. Attached to binding post 14 are conductors 15 and 17, which are respectively connected to switches 16 and 18. The switch 16 85 is connected by conductor 22 to electric lamp 23 installed in front of the conductor of the train, and from the lamp a circuit is made through conductor 24, switch 25, conductor 26 to ground. From switch 16 a conductor 27 90

ply being grounded, a pair of sliding contact members adapted to make electrical contact with said trolley conductors, a circuit including one of said sliding contact members, a circuit breaker, said source of supply, a second circuit breaker, a signal lamp and said other sliding contact, a second circuit including one of said sliding contact members, a signal lamp, a circuit breaker and ground, and a third circuit connected to the positive terminal of said source of supply including a circuit breaker and the other of said sliding contact members.

15 In testimony whereof I affix my signature.

RAFAEL PRADO PALENZUELA.
